US00D683277S

(12) United States Design Patent
McCoy

(10) Patent No.: US D683,277 S
(45) Date of Patent: * May 28, 2013

(54) MOUNTING DEVICE FOR UNDER BED
HITCH MOUNTING SYSTEM

(75) Inventor: Richard W. McCoy, Granger, IN (US)

(73) Assignee: Cequent Performance Products, Inc.,
Plymouth, MI (US)

() Term: 14 Years

(21) Appl. No.: 29/429,779

(22) Filed: Aug. 16, 2012
